UNITED STATES PATENT OFFICE.

MARINUS LESLIE MILLER, OF SOURABAYA, JAVA.

MECHANICAL DIGGER.

1,366,741.

Specification of Letters Patent. Patented Jan. 25, 1921.

Application filed August 11, 1919. Serial No. 316,909.

To all whom it may concern:

Be it known that I, MARINUS LESLIE MILLER, a subject of the King of Great Britain, residing in Sourabaya, Java, have invented certain new and useful Improvements in Mechanical Diggers, of which the following is a specification.

This invention relates to mechanical diggers and it has for its object certain improvements in such diggers designed to secure their more efficient operation.

The invention further provides an improved form of spade for use in mechanical diggers, and means for emptying or clearing the earth from said spades.

In order that the invention may be better understood drawings are appended in which:—

Figure 1 is a side view of a digger embodying the present improvements.

Fig. 2 is a plan.

Fig. 3 is a side view of one of the spades showing the arrangement of the clearing mechanism.

25 Fig. 4 is a plan showing two spades respectively at the end of their rear and forward strokes.

Fig. 5 is an end view of the spade shown in Fig. 3.

30 Fig. 6 is a side view of a spade with the operating mechanism therefor.

Fig. 7 is a view showing diagrammatically one complete cycle of movement.

In the accompanying drawings the invention is shown as applied to a motor driven machine, and in which drawings while the whole machine is illustrated only such parts thereof as are essential to the proper understanding of the invention are identified and will be described.

Referring to the drawings 1 indicates the frame of the machine formed of channel iron, tapering somewhat toward the front of the said machine, said frame being supported by means of driving wheels 2 and a steering wheel 3 located in the front of the machine. The machine is driven by means of a motor indicated generally by 4, mounted in any convenient manner upon the frame 1, a suitable gear box being provided at 5 to the main shaft 6 of which the motor is coupled. 7 indicates a shaft which may if desired be coupled directly to the engine shaft and 8 indicates a second shaft connected to shaft 6, the gearing in box 5 being so arranged that only one of the shafts 7 and 8 can be

driven at the same time. 9 indicates a differential gear operated by bevel wheels, 10, 11, respectively secured to shaft 7 and to the shaft 12, operated through the differential gear, the shaft 12 serving to give backward or forward motion to the driving wheels 2.

Disposed at the back of the machine and supported by the frame 1 of the machine is the digging mechanism comprising eight arms 13 pivotally mounted at their lower ends upon the main shaft 14 supported by the frame of the machine. 65

As will be seen on reference to Fig. 2 three of the arms 13 upon each side of the machine are connected at their upper ends by means of a rod 13^a, the two center arms 13 being connected by a rod 13^b. Pivotedly connected to the upper ends of the center of the three arms upon each side of the machine are bars 15 formed of channel iron. A similar bar 15 is provided for the arms in the center of the machine. The bars at their inner ends are secured together and have attached to them a nut 16 engaging a screw 17 mounted in a suitable frame and operable by means of a hand wheel 18. By this means the arms may be swung in either one or other direction to advance or withdraw the digging mechanism.

The main shaft 14 before referred to is driven by means of the bevel pinion 19 engaging the smaller pinion 20 which latter is keyed to shaft 8. Secured to shaft 14 are two pinions 21, 22, engaging the toothed wheels 23, 24, formed in two parts secured to a 6 throw crank shaft 25 supported by bearings formed in the aforesaid arms 13.

Also secured to the shaft 25 are chain wheels 26, 27, made in two parts secured together in any convenient manner. The chain wheels drive other chain wheels 28, 29, formed in one piece with or secured to other chain wheels 30, 31, whereby power is transmitted from wheels 26, 27, to shaft 12 upon which are mounted free chain wheels 33, 34. Thus when shaft 12 is in gear with shaft 7 the chain wheels 33, 34, remain stationary.

Freely mounted upon shaft 14 carrying the aforesaid arms 13 are other arms 35 the outer ends of which are pivotally connected to rods 36 forming the shafts of the spades 37, the upper ends of the rods 36 being connected to the pins of the respective cranks of shaft 25. 110

The spades indicated by 37 are as shown upon the drawings arranged in pairs, one

right and the other left hand, each spade upon the discharge side having upon the underside a web 38 while upon the other edge a web 39 is provided upon the upper 5 surface of the plate.

The spade at the upper end is provided with a plate 40 shaped as shown, and pivotally connected at 41 to a plate 42 at the upper end of the blade of the spade. 43 indicates a rod pivotally connected at its outer end to the plate 40 and at its opposite end connected to a collar 44 sliding freely upon the rod 45 supported at its end in brackets 46, 46¹, secured to the rod or shaft 36 of the spade. 47 indicates a spring connected at one end to the plate 40 and at the other to an arm upon the bracket 46¹ and by means of which spring as will be hereinafter more fully explained the plate 40 is returned to its 20 normal position after being operated to clear the earth from the spade.

Sliding freely upon rod 43 is a slipper 48 to which is connected the outer end of a rod 49 which rod at its inner end is provided 25 with a strap 50 surrounding a grooved collar 51 secured to the crank shaft 25.

13¹ indicates an extension of the arm 13 at the lower end of which is revolvably mounted a disk 53 adapted to contact with 30 the ground and so start the trench.

The action of the parts just above described is as follows:—

Assuming a spade to be in its lowest position, as the crank acts to raise the spade the 35 sliding collar 44 to which plate 40 is connected comes into contact with the slipper 48 connected to rod 49 whereby the plate 40 is caused to sweep across the spade being at the end of the up stroke in the position 40 shown to the left of Fig. 4 the earth being discharged upon the right hand side of the spade the plate 40 being retained at the side of the spade by means of the spring 47.

The path of the spade during one complete 45 rotation of the crank shaft is shown in Fig. 4 the distance between the horizontal lines *w y* showing the depth of the trench.

Claims.

1. In a digging machine a plurality of 50 crank actuated spades, means for clearing the earth therefrom mounted upon said spades said clearing means being caused to sweep across the spades during the upward movement thereof and to project the earth 55 to one side, means for propelling the machine and operating the spades and means whereby the spade mechanism may be brought into or thrown out of operation.

2. In a digging machine a plurality of 60 crank actuated spades, plates pivotally mounted upon said spades, means for operating said plates whereby they are caused to sweep across the upper surface thereof during the upward movement thereof and to 65 project the earth to one side, means for pro-

pelling the machine and operating the spades, and means whereby the spade mechanism may be brought into or thrown out of operation.

3. In a digging machine a plurality of 70 spades, a crank shaft having a plurality of cranks to which the spade shafts are connected, guide bars mounted upon the spade shafts, slippers upon said guide bars, rods connected at one end to the crank shaft and 75 at the other to the slippers, bosses slidable on the guide bars, plates pivotally mounted upon the blades, springs operating to move the plates in one direction, rods connecting the plates with the bosses, means for propelling the machine and operating the spade 80 mechanism and means whereby the spade mechanism may be brought into or thrown out of operation.

4. In a digging machine a plurality of 85 spades, a crank having a plurality of cranks to which the spade shafts are connected, guide bars mounted upon said spade shafts, slippers upon said guide bars, rods pivotally connected at one end to the crank shaft and 90 at the other to the slippers, bosses slidable on the guide bars, plates pivotally mounted upon the upper ends of the blades, springs operating to move the plates in one direction, rods connecting the plates with the 95 bosses whereby the plates are operated against the action of the spring, links controlling the radial movement of the spades, means for propelling the machine and operating the spades, and means whereby the 100 spade mechanism may be brought into or thrown out of operation.

5. In a digging machine a shaft, brackets pivotally supported on said shaft, a crank shaft supported in said brackets having a 105 plurality of cranks, a plurality of spades to which the crank shafts are connected, guide bars carried by supports mounted on the spade shafts, slippers upon said guide bars, rods pivotally mounted upon said crank 110 shaft at one end and at the other connected to the slippers, bosses slidable on the guide bars, angle plates pivotally mounted at the upper ends of the blades of the spades, springs connected at one end to one of the 115 supports of the guide bars and at the other to said angle plates a screw operated body, links connected at one end to said body and at the other to the swinging brackets carrying the crank shaft, means for operating 120 said screw to rock said swinging members, means for propelling the machine and operating the spades, and means whereby the spade mechanism may be brought into or thrown out of operation.

6. In a digging machine a shaft, pinions thereon, brackets swingingly mounted on said shaft, a crank shaft carried by said swinging brackets, pinions on said crank shaft engaging the pinions on the driving 125 130

shaft, chain wheels on said crank shaft, other chain wheels on the driving shaft, chains passing around said chain wheels, other chain wheels connected to said latter 5 wheels and clutched to the said driving shaft, a shaft operating the driving wheels of the machine, chain wheels clutched to said shaft, a chain whereby motion is transmitted from the chain wheels clutched to the 10 driving shaft, a motor, a gear box, a shaft driven through the said gear, a second shaft also capable of being driven by said gear, means for driving either shaft at will, a bevel wheel upon the first shaft a bevel wheel 15 engaged by said first bevel wheel upon the driving shaft, a bevel wheel upon the second shaft, a bevel wheel engaged thereby upon the shaft operating the driving wheels, spades operated by the crank shaft, and 20 spade clearing means upon said spades.

7. In a digging machine a shaft, pinions thereon, brackets swingingly mounted on said shaft, a crank shaft carried by said swinging brackets, pinions on said crank 25 shaft engaging the pinions on the driving shaft, chain wheels on said crank shaft, other chain wheels on the driving shaft, chains passing around said chain wheels, other chain wheels connected to said latter wheels 30 and clutched to the said driving shaft, a shaft operating the driving wheels of the machine, chain wheels clutched to said shaft, a chain whereby motion is transmitted from the chain wheels clutched to the driving 35 shaft, a motor, a gear box, a shaft driven through said gear, a second shaft also capable of being driven by said gear, means for driving either shaft at will, a bevel wheel upon the first shaft, a bevel wheel engaged 40 by said first bevel wheel upon the driving shaft, a bevel wheel upon the second shaft, a bevel wheel engaged thereby upon the shaft operating the driving wheels, spades operated by the crank shaft, plates pivotally 45 mounted upon said spades adapted to sweep across the upper surface thereof and to project the earth to one side.

8. In a digging machine a shaft, pinions thereon, brackets swingingly mounted on 50 said shaft, a crank shaft carried by said swinging brackets, pinions on said crank shaft engaging the pinions on the driving shaft, chain wheels on said crank shaft, other chain wheels on the driving shaft, 55 chains passing around said chain wheels, other chain wheels connected to said latter wheels and clutched to the said driving shaft, a shaft operating the driving wheels of the machine, chain wheels clutched to said 60 shaft, a chain whereby motion is transmitted from the chain wheels clutched to the driving shaft, a motor, a gear box, a shaft driven

through the said gear, a second shaft also capable of being driven by said gear means for driving either shaft at will, a bevel wheel 65 upon the first shaft, a bevel wheel engaged by said first bevel wheel upon the driving shaft, a bevel wheel upon the second shaft, a bevel wheel engaged thereby upon the shaft operating the driving wheels, spade 70 shaft connected to the cranks of the crank shaft, guide bars mounted upon the spade shafts, slippers upon said guide bars, rods connected at one end to the crank shaft and at the other to the slippers, bosses 75 slid- able on the guide bars, plates pivotally mounted upon the blades, springs operating to move the plates in one direction and rods connecting the plates with bosses.

9. In a digging machine a shaft, pinions 80 thereon, brackets swingingly mounted on said shaft, a crank shaft carried by said swinging brackets, pinions on said crank shaft engaging the pinions on the driving shaft, chain wheels on said crank shaft, 85 other chain wheels on the driving shaft, chains passing around said chain wheels, other chain wheels connected to said latter wheels and clutched to the said driving shaft, a shaft operating the driving wheels 90 of the machine, chain wheels clutched to said shaft, a chain whereby motion is transmitted from the chain wheels clutched to the driving shaft, a motor, a gear box, a shaft 95 driven through the said gear, a second shaft also capable of being driven by said gear, means for driving either shaft at will, a bevel wheel upon the first shaft, a bevel wheel engaged by said first bevel wheel upon the driving shaft, a bevel wheel upon the 100 second shaft, a bevel wheel engaged thereby upon the shaft operating the driving wheels, spade shafts connected to the cranks of the crank shaft, guide bars mounted upon said spade shafts, slippers upon said guide bars, 105 rods pivotally connected at one end to the crank shaft and at the other to the slippers, bosses slid- able on the guide bars, plates pivotally mounted upon the upper ends of the blades, springs operating to move the plates in one direction, rods connecting the plates with the bosses whereby when the slippers contact with the bosses the plates are operated against the action of the springs, links controlling the radial movement of the 110 spades and means for propelling the machine and operating the spades.

In testimony whereof I affix my signature in the presence of two witnesses.

M. LESLIE MILLER.
